UNITED STATES PATENT OFFICE.

LEMON L. OSBORN, OF LOS ANGELES, CALIFORNIA.

HYDRODYNAMIC POWER MACHINE.

Application filed May 12, 1925. Serial No. 29,818.

This invention relates to hydrodynamic power machine, and the object of the invention is the production of a hydraulic motor which is simple in construction and efficient in operation, and comprises comparatively few parts.

Another object of the invention is the construction of a power machine, which utilizes water as the motive power and which machine or motor is compactly constructed as well as being positive in operation.

This efficient machine is an improvement upon the machine or motor disclosed in my prior United States Patent No. 962,382, patented June 21, 1910.

With the foregoing and other objects in view, my invention comprises certain combinations, constructions and arrangement of parts as will be illustrated in the accompanying drawings, described in the following specification, and more particularly pointed out in the appended claims.

In the drawings:

Figure 1 is a plan view of a machine constructed in accordance with the present invention.

Figure 2 is a side elevation of the same.

Figure 3 is a front or inlet end of the invention.

Figure 4 is a rear or discharge end elevation.

Figure 5 is a fragmentary side view of the machine, while

Figure 6 is a fragmentary end view of the same part of the machine.

Figure 7 is a fragmentary perspective view of the discharge end of my machine.

Figure 8 is an enlarged fragmentary view in elevation of the apparatus.

Referring to the drawings by numerals, 1 designates the body or casing of my machine, the same being divided into float chambers 2 and 3; bucket chambers 4 and 5, and a space 6 for an inlet valve mechanism. A distributing launder 7 is provided for allowing water to be fed to the four compartments 2, 3, 4 and 5. Two floats 8 and 9 are in compartments 2 and 3 respectively, and are provided, near each end with a plate 10 to

which the lower ends of rods 11 are connected. Buckets 12 and 13 are mounted in compartments 4 and 5 respectively. These buckets are each fitted with plates 10 like the floats are. To the plates 10 of the buckets are attached the lower ends of rods

14. At the discharge end of each bucket compartment or chamber is a hinged door or discharge gate 15, Figure 7.

A main central shaft 16 is journaled at its ends in brackets 17. By means of a rocker arm 18 and links 19 (Fig. 3) this shaft 16 is connected to whatever machine is to be operated. The links 19 are, therefore, attached to what might be called the inner ends of shaft 16, whereas on the outer end of shaft 16 is fastened a rocker arm 20, through the outer end of which passes a stop rod 21, Figs. 2 and 7; this rod 21 is provided with a pair of stops 22 that are threaded on the rod, for the purpose hereinafter described.

Brackets 23 are mounted on the body or casing 1, and suitably journaled on the upper end of these brackets are shafts 24 and 25. Vertical rods 11, which are connected at their lower ends to the floats are pivotally connected at their upper ends to the outer ends of rocker arms 26. The inner ends 27 of these arms 26 are slotted, yoke shape to permit the extension to reach beyond shafts 24 and 25 for connecting the links 28, Figure 3. These links 28 form connection from inner end of arm 26 to outer end of arm 18 and to upper ends of rods 14. Arm 18 is secured to the inner end of shaft 16. Rocker arm 20 is securely fastened at its inner end to the outer end of shaft 16; through the outer end of arm 20 extends said rod 21 with said adjustable nut-like stops 22, whereby the stops 22 can be adjusted on the rod 21 for regulating the stroke of arms 29 and 30 fixedly secured to shaft 31. Rod 21 is pivotally connected at its lower end to one of the arms 29, Fig. 7.

Shaft 31 is journaled upon bearings 32 which bearings are mounted upon brackets 33 of casing 1. Keyed to shaft 31 is an upstanding arm 34. A rod 35 is pivotally connected at its outer end to the upper end of said arm 34, and its inner end is pivotally connected to arm 36. Arm 36 is keyed to latch shaft 37, which shaft 37 is suitably journaled on the sides of the casing 1. 38 is a valve shaft; the ends of this shaft are suitably journaled on the side walls of the casing 1. Connected to shaft 38 are butterfly valves or gates 39, 40, 41 and 42, located in front of compartments or chambers 2, 3, 4 and 5 respectively.

Referring particularly to Figure 7:

A rod 43 is fastened to toggle device 44, and at its upper end extends through slot 45 in the upwardly extending arm 29 fastened to shaft 31. This rod 43 is provided 5 with adjustable stops 46 which perform in similar manner to stops 22. The toggle device 44 is pivotally connected at one end to a gate 15 and its other end is pivotally connected at 47 to the slotted bracket 48. A 10 rod 43^a is pivotally connected at its lower end to toggle device 49, this device being connected at its inner end to a gate 15 and at 15 50 to bracket 51. The upper end of rod 43^a extends through the outer slotted end of the downwardly extending arm 29, on shaft 31 and on this rod 43 are adjustable stops 52 for limiting the stroke of arm 29. I employ two rods 53 which are connected at 20 their upper ends to arms 30 and are also pivotally connected at their lower ends to 25 toggle devices 54. The inner ends of toggle devices 54 are pivotally connected at 55 to gates 56, and their outer ends are pivotally connected at 57 to the upper ends of brackets 58. It is to be noted that rods 43 and 43^a work in the slots 59 of brackets 48 and 51. The action of this hydrodynamic power machine, in one complete cycle, is as follows: 30 As shown in Figure 1, gates or butterfly valves 39 and 42 are in a vertical position, or closed, and butterfly valves 40 and 41 are in a horizontal position, or open. Thus water entering through the distributing launder 7 flows into compartments 3 and 4. 35 Water entering compartment 3 flows under the float 9. Water entering compartment 4 enters bucket 12. The weight of water entering bucket 12 will, through its connecting links 14 and arms 26, tend to rotate shaft 40 16, while at the same time, the water in compartment 3 will tend to raise the float 9, which in turn, through its connecting links 11, arm 26, extension 27 and links 28, will tend to rotate shaft 16 in the same direction 45 as the weight of the water in bucket 12. Shaft 16 thus being made to rotate will through the upward movement of arm 20, at its slotted outer end, strike the upper stop 22, raising the inner end of arm 29 and thus 50 cause a clockwise rotation of shaft 31 (Figs. 2 and 7). This rotation of shaft 31 will, through the outer end of arms 29 and 30, cause a downward movement of rods 43^a and 53, thus causing toggle devices 49 and 54 55 to straighten closing gates 15 and 56 of one set; there are two sets of gates, one controlling the discharge of a bucket chamber and the other controlling the discharge of a float chamber; when the gates of one set are closed the gates in the other set open so that the water may be discharged from the chambers of one set while the chambers of another set are being filled, that is, the water moving into the chamber under one of the 60 65 floats and into the bucket in a chamber of

the same set so that a float is being raised and a bucket is being filled at the same time in the same set, whereas in the other set, with the gates open, the water is being discharged out of a chamber from under a float 70 and out of a bucket in another chamber. The same rotation of shaft 31 will cause one set of gates to open while at the same time closing the gates of the other set. 75

Shaft 38, through its revolution of 90 degrees will cause butterfly valves 40 and 41 to be brought from a vertical to a horizontal open position, as shown in Figure 1, and butterfly valves 39 and 42 from a horizontal position to a vertical closed position as 80 shown, thus closing passage to compartments 2 and 5, and opening passage and allowing water to flow into compartments or chambers 3 and 4. The gate 15 of compartment 5 and the gate 56 of compartment 2 85 having been open, through action of shaft 31 and its cooperating devices, and gate 56 and the other gate 15 having been closed, this condition of the gates will allow the escape of the water from one set resulting 90 in the movement of the buckets and floats to rotate the shaft 16.

The stops 22, 46 and 52 are for the purpose of regulating the stroke of the arms in accordance with the rotation of shaft 31, 95 it being desirable to regulate the opening of all discharge gates. The stops 46 and 52 are also useful in securing an accurate movement of the toggle devices 44 and 49 to cause the tight closing of the gates to 100 which they are attached.

From the foregoing it will be seen that my machine is very simple in operation in that there are two sets of floats and buckets, each set comprising a float and a bucket, 105 means for alternately supplying liquid simultaneously to a bucket in one set and to or under the bottom of the float in the same set, whereas in the other set, the water is being discharged from under the float and at the same time the bucket of this set is being emptied; these sets of floats and buckets are connected by links or rods and arms to a rotatable shaft, from which shaft power is 110 derived for driving machinery. 115

Any suitable valve mechanism may be assembled at the intake end of the machine contiguous to the launder 7 to actuate rod 35 in time relation for causing the uniform movement of the elements of one set of buckets and floats in conjunction with the movement of the bucket and float in the other set; this valve mechanism comprising the shaft 38 and the butterfly valve as hereinbefore described to control the passage of liquid or water through the launder into the compartments or chambers, as hereinbefore 120 specifically described.

What I claim is:

1. In a machine of the class described, the 130

combination with a casing, of sets of operated devices in said casing, each of said sets including a float and a bucket, means for alternately supplying liquid simultaneously

5 to a bucket in one set and to or under the bottom of the float in the same set, a shaft, means connecting each set of said devices to said shaft, whereby the shaft is rotated when liquid is supplied to said sets of devices, and valve means in said casing and controlling the supply of liquid to said sets of operated devices.

2. In a machine of the class described, the combination with a casing, of sets of operated devices in said casing, each set including a vertically movable float and a vertically movable bucket, valve means at the ends of said sets for controlling the passage of liquid to and from said devices, a shaft, means connecting said operated devices to said shaft whereby when liquid is supplied to the devices, said liquid will alternately operate one bucket and one float in each device for causing the same to move 25 in a vertical plane for imparting rotary movement to said shaft, and means connected to said shaft and said valve means for operating the valve means in timed relation to said buckets and floats for opening 30 and closing the valve means for permitting the passage of liquid through the casing.

3. In a machine of the class described, the combination with a casing, of a pair of floats and a pair of buckets mounted in said casing, a driven shaft mounted upon said casing, separate means connected to said driven shaft and connecting said shaft, floats and buckets thereto, each separate means being connected to a float and a bucket 40 whereby when liquid is passed through said casing one float is raised and the other float is lowered and one bucket is raised and another bucket is lowered, and valve means operated in timed relation with said floats and buckets for controlling the passage of water through the casing and to said buckets and under said floats.

4. In a machine of the class described, the combination of a casing provided with 50 an inlet end and an outlet end, of a plurality of floats and a plurality of buckets movably mounted in parallel position between the inlet and outlet ends of said casing, valve means between said floats and said buckets and the inlet end of the casing for controlling the flow of liquid to the buckets and under the floats, valve means within the casing between the floats and the buckets and the outlet end of the casing for controlling 60 the passage of liquid from the buckets and from under the floats, and means operating in timed relation with the floats and the buckets and connected to said valve means for causing the same to open and close in co-operation with said floats and said buck-

ets for permitting the passage or flow of liquid to and from the buckets and under the floats and thence from under said floats.

5. In a machine of the class described, the combination of a casing provided with a chute-like inlet end and with a discharge end, a driven shaft extending longitudinally of the casing and journaled thereon near its center, a vertically movable float and a vertically movable bucket in the casing at 75 each side of said shaft, means independently connected to the shaft and to one bucket at one side of the shaft and to one float at the other side of the shaft, whereby upward movement of a bucket and downward movement of a float will impart rotary movement to said shaft, valve means for controlling the supply of liquid alternately to one bucket and to one float and then permitting liquid to be supplied to the other float and the other bucket, and additional valve means co-operating with said shaft and operated in timed relation with the floats and the buckets for permitting liquid to be discharged from the buckets and the floats, substantially as described.

6. In a machine of the class described, the combination with a casing provided with an inlet and an outlet end, of a centrally positioned shaft journaled upon said casing, a vertically movable float and a vertically movable bucket in said casing at each side of said shaft, means connecting the shaft independently to a bucket at one side and to a float at the other side, whereby said floats and buckets are connected to the shaft in sets, valve means in the casing for alternately controlling the passage of water to and from the bucket and the float in one set and then to the bucket and float in the other set 100 whereby said shaft is rotated.

7. In a machine of the class described, the combination with a casing provided with an inlet and an outlet end, of a driven shaft journaled upon said casing, floats and buckets in said casing between the inlet and outlet ends, means connecting said floats and buckets in pairs to said shaft whereby when one bucket and one float is moved by water passing through the casing, the shaft will be 110 rotated, swinging valve means at both ends of said buckets and said floats, and toggle and link means connected to said valve means and to said driven shaft and actuated by the driven shaft when said floats and buckets are 120 operated by water passing through the machine to open and close the swinging valve means.

8. In a machine of the class described, the combination of a casing provided with an inlet and an outlet end, of a pair of vertically movable floats and a pair of vertically movable buckets arranged in parallel position within said casing and between said ends, a driven shaft journaled upon said casing 130

- above said floats and buckets, means connecting said shaft to said buckets and floats in pairs, each pair including a bucket and a float, swinging valves for controlling the passage of liquid to said floats and said buckets positioned in front of the floats and buckets and between the same and the inlet end of the casing, hinged gate valves in said casing near the outlet end of said casing and at the ends of said floats and buckets, toggle means connected to said gate valves near the outlet ends of the casing, a stop device co-operating with said driven shaft and connected to said toggle means for operating and closing said gate valves when said driven shaft is operated, a rod, means connecting one end of said rod to said stop device and to said toggle means, and means connecting the other end of said rod to said swinging valves at the front end of said floats and said buckets for operating said swinging valves in timed relation to the movement of the driven shaft and the gate valves.

9. In a machine of the class described, the combination with a casing, of vertically movable floats and vertically movable buckets in said casing, a driven shaft journalled upon said casing, means connecting a float and a bucket independently to said driven shaft whereby the floats and buckets are arranged in pairs and connected in pairs to said driven shaft, swinging valves at the front of said floats and said buckets, an operating mechanism for said gate valves including a stop device and toggles, means connecting said stop device to said driven shaft, whereby movement of the driven shaft will operate to close and open said gate valves, and means extending parallel with the floats and the buckets and connected to said stop device and to the swinging valves for operating the swinging valves in timed relation to the movement of the valves and buckets for permitting the swinging valves to allow water to enter only one bucket and under one float at the same time for moving the bucket and the float to impart rotary movement to the driven shaft.

10. In a machine of the class described, the combination with a casing, of a plurality of parallel vertically movable floats and buckets in said casing, a driven shaft extending longitudinally of the casing and journalled thereon, rocker arms and links fastened to the shaft and pivotally connecting said floats and said buckets in pairs to said shaft, each pair including a float and a bucket, valve means in the casing at the ends of said buckets and said floats, and means operated by the driven shaft and connected to all of the valve means, whereby when the floats and buckets are operated, said valve means will be operated to permit the passage of water through the machine, acting upon only one pair of said floats and buckets at a time, for imparting rotary movement to said driven shaft.

11. In a machine of the class described, the combination of a casing provided with a distributing launder and a discharge end, pairs of vertically movable floats and buckets in said casing at its center and arranged in parallelism, a driven shaft extending longitudinally of the casing and journalled thereon above said floats and said buckets, arms fixedly secured to said shaft, links pivotally connecting said arms to said floats and said buckets, said floats and said buckets being arranged or connected in pairs to said driven shaft, each pair including a bucket and a float, a transverse shaft across the casing near said distributing launder, swinging valve means connected to said transverse shaft for controlling the passage of water through said distributing launder to said floats and buckets, gate valves near the discharge end of said casing and at the rear of the outlet ends of said buckets and floats, control means connected to said driven shaft and said gate valves whereby the gate valves are opened and closed upon rotation of the driven shaft, a rod extending longitudinally of the casing and parallel with said floats and buckets, means connecting one end of said rod to said control means whereby movement of the control means will operate said rod, and means connecting the other end of said rod to said transverse shaft whereby when said rod is operated through the control means, movement will be imparted to said transverse shaft for operating the swinging valves for opening and closing said swinging valves for permitting water to alternately enter the buckets and also pass under the floats for raising the same and thereby imparting rotary movement to the driven shaft.

12. In a machine of the class described, the combination of a casing provided with float compartments and with bucket compartments, floats in said float compartments and buckets in said bucket compartments, means connecting said floats and buckets into sets whereby when one bucket in a set is being filled the float of said set will be raised and the bucket in the other set will be emptied and the float in the same set lowered, said casing provided at one end of said compartments with discharge gates, slotted brackets over the gates of the bucket compartments, toggle devices pivotally connected at one end to the gates under said slotted brackets and pivotally connected at their other end to said brackets, means connecting said toggle devices through said slotted bracket to said gates of the float compartments, and means connected to said connecting means for opening the gate of one of the bucket compartments and the gate of one

of the float compartments while at the same time closing the gate of one of the bucket compartments and the gate of the other float compartment.

- 5 13. In a machine of the class described, the combination of a casing provided with float compartments and with bucket compartments, floats in said float compartments and buckets in said bucket compartments,
- 10 means connecting said floats and buckets into sets whereby when one bucket in a set is being filled the float of said set will be raised and the bucket in the other set will be emptied and the float in the same set lowered,
- 15 said casing provided at one end of said compartments with discharge gates, brackets carried by the casing contiguous to the gates of the bucket compartments, toggle devices attached to the brackets and to the gates of
- 20 the bucket compartments, and means connected to said toggle devices and to said gates of the float compartment whereby a gate of a bucket and a gate of a float compartment is moved to an open position while another
- 25 gate of a bucket compartment and a gate of a float compartment is being closed.
14. In a machine of the class described, the combination of a casing provided with a pair of float compartments and with a pair
- 30 of bucket compartments, vertically movable buckets in said bucket compartments and vertically movable floats in said float compartments, means connecting said buckets and said floats whereby one bucket is filled
- 35 and one float is raised at the same time another bucket is emptied and another float
- is lowered, said casing provided with hinged discharge gates at the same ends of said compartments, upstanding brackets carried by the casing contiguous to the gates of said
- 40 float compartments, toggle devices pivotally connected at one end to said upstanding brackets and at their opposite ends to said gates of said float compartments, a pair of slotted brackets over said gates of the bucket
- 45 compartments, toggle devices pivotally connected at one end to said gates of the bucket compartments and at their opposite end to said slotted brackets, rods pivotally connected at their lower ends to all of said toggle
- 50 devices, some of said rods extending through said slotted brackets, a horizontal shaft journalled upon said casing, arms fixedly secured to said shaft and movably connected to all of said rods, a valve mechanism for controlling the discharge of water into all of
- 55 said compartments, and means operating with said valve mechanism and movably connected to said shaft whereby when the valve mechanism is operated said shaft will
- 60 be moved in unison for operating its arms and said rods whereby the toggle devices will be operated so that one gate of one bucket compartment and one gate of one float compartment will be opened and one
- 65 gate of one bucket compartment and one gate of one float compartment will be closed, substantially as shown and described.

In testimony whereof I hereunto affix my signature.

LEMON L. OSBORN.
